UNITED STATES PATENT OFFICE.

FRANK B. YINGLING, OF HAMILTON, OHIO.

TILE-PRESS.

1,268,909.

Specification of Letters Patent. Patented June 11, 1918.

Application filed May 9, 1914. Serial No. 837,536.

To all whom it may concern:

Be it known that I, FRANK B. YINGLING, a citizen of the United States, and resident of Hamilton, Butler county, State of Ohio, 5 have invented certain new and useful Improvements in Tile-Presses, of which the following is a specification.

The present invention relates to improvements in tile presses. Such presses are required to operate upon clay or other suitable material in a powdered or fine granular form, which material has a tendency to entrap the air within itself when pressure is applied, resulting frequently in "wind blown" or "laminated" tile, owing to the contained air preventing close union of the particles of clay. It is necessary that the finished tile be firm and strong and this can only be accomplished by subjecting the material to great pressure and insuring that the air contained in the clay in its normal loose condition is permitted to escape before the pressing operation is completed. As the dies by which the pressing is effected 20 must fit rather snugly within the mold case, they have a tendency to prevent the escape of air as freely as would be the case if the dies were only loosely fitted within the mold. The tile must, of course, be uniform 25 throughout, which requires that the material be evenly disposed in the mold and not unduly packed, as it is loosely charged therein. The clay is tempered by a certain amount of moisture, which is kept as near uniform 30 as possible, to produce the best results. Variation of the temper of the clay varies the density of the tile, and to counter-act this and obtain, as near as possible, uniform pressures, it is necessary to vary the amount 35 of the charge.

The dies must be kept clean so that the resulting tile will be smooth, without pit marks or defects caused by the clay adhering to either the top or bottom dies and heat 40 must be supplied around the die and mold cavity to keep the damp clay from unduly adhering to the dies.

A press which meets all of the requirements above noted is provided by the present invention which will be described in connection with the embodiment thereof illustrated in the accompanying drawings, in which,

Figure 1 is a side elevation;

Fig. 2 is a front elevation;

Fig. 3 is a rear elevation;

Figs. 4 to 9 illustrate the several relative positions which the essential parts of the machine occupy at different times in each cycle of operation. In these figures several 60 of the parts are shown conventionally as the views are more or less diagrammatic;

Fig. 10 is a detail view partly in section of the upper actuating toggle member and its supporting means;

Fig. 11 is a more or less diagrammatic view illustrating the means preferably employed for limiting downward movement of the lower die at one step of the cycle of operation produced by each rotation of the 70 power shaft when it is required that the tile be pressed near the top of the mold or at an intermediate place between the top and bottom of the mold case.

In some of its features as regards arrangement of parts, etc., the improved press for tile is similar to machines of the same general type heretofore employed in the manufacture of brick, comprising for example, a main supporting frame including 80 side members A, a main power shaft B mounted in suitable bearings in said frame, a mold box or casing C, a lower plunger or die D, an upper, toggle actuated, plunger or die E, a pitman F connecting the die toggle with 85 a crank on the power shaft B, a clay reservoir or hopper G and a reciprocating mold charging device adapted to be reciprocated by suitable cam mechanism actuated by the shaft B to convey a charge from the hopper 90 G to the mold casing.

The support H for the lower die D is carried by slides I fitted in suitable guides on the framework A; and the shaft K constituting the pivotal support for the upper 95 member of the toggle L is mounted in bearings in these slides I. The bearing portions of the shaft are positioned eccentrically to the intermediate body section and to one end of the shaft is suitably secured a crank M 100 which is connected by a rod m with one arm of a bell crank M' mounted on the frame of the machine and having its other arm provided with a roller m' with which a cam M' on the power shaft B co-operates, whereby 105 the eccentric, toggle supporting, shaft will be rocked in its bearings during each rotation of the shaft B. In the embodiment of the invention illustrated the crank M is provided with a sleeve that surrounds the shaft 110

K and is connected by bolts m^2 to a collar m^3 that is keyed or otherwise rigidly secured on the shaft. As shown in Fig. 1, the connecting rod m is of such construction that the length thereof may be varied as desired to vary the angular relation between the cranks, M, M', and thereby control the amount of second pressure adjustment of the toggle L produced by rocking the shaft K.

10 The pitman F is provided on its lower face with a cam plate F' that is adapted to coöperate with a roller F² mounted in the main frame to effect simultaneous vertical movement of both of the dies, for ejecting the tile from the mold. The capacity of the mold or the quantity of material it can receive is regulated by stop S and hand-wheels S² and screws S'.

Clay is suitably supplied to the hopper 20 or receptacle G and a quantity thereof sufficient to form a tile or number of tiles to be produced at each complete operation of the machine is periodically transferred from the hopper to the mold casing by a reciprocating 25 charging device N. It will be understood that with a given adjustment of the parts of the toggle mechanism the ultimate travel of the die plates toward each other is the same, thus producing tile of uniform thickness; but 30 the density is regulated by the amount of clay in the mold. The charging device comprises a rectangular shaped frame and a rearwardly extending plate or cut off member N', which prevents escape of material 35 from the hopper when the tubular section of the charging device is out of alinement with the opening in the bottom of said hopper. The charging device is provided at each side with a rearwardly extending rod or link n, 40 the rear ends of which rods are connected by a cross bar n' and are adapted to be engaged by a pair of arms n², mounted to rock about a common axis in the frame of the machine and one of which has at one end an upwardly 45 extending arm n³ which at its outer end is provided with a roller n⁴ coöoperating with a cam N⁴ on the main power shaft B.

By the construction and arrangement of parts illustrated herein the charge of clay 50 within the mold box or casing is subjected to two distinct compressing actions by a single rotation of the main power shaft, the second of said compressing actions being materially stronger or heavier than the first. During 55 the interval between said successive compressions the charge is relieved from pressure of the dies so that the air entrapped in the mold may freely escape. The manner in which these several operations are effected 60 will be clear from a consideration of the drawings, particularly of Figs. 4 to 9.

In Fig. 4 the parts are shown in the positions occupied at the completion of a pressing operation with the lower die raised to the 65 top of the mold box or casing and the upper

die separated therefrom so that the finished tile may be pushed from the lower die onto a suitable table or conveyer. The charging device N, as the shaft B turns in the direction indicated by the arrow in Fig. 4, is actuated 70 by the cam thereon to force the completed tile from the lower die and carry a suitable charge of clay over the lower die in the mold box or casing. The relative positions of the

several parts at the completion of the forward stroke or movement of the charging device are illustrated in Fig. 5. Referring to this figure it will be seen that the pitman F has been advanced so as to open the toggle L to a greater extent than in Fig. 4, but the lower die is maintained in its uppermost position by the engagement between the cam F' and roller F². In moving from the position shown in Fig. 4 to that shown in Fig. 5 the bell crank M' is actuated to return the 85 arm M and eccentric shaft K to the position in which the upper end of the toggle L is at its maximum distance from the mold box and lower die. It will be seen that the stroke of the charging device of such length that 90 at the forward limit thereof a portion of the charge receptacle is beyond the front wall of the mold box or casing. This is important as it avoids any possibility of the clay being undesirably caked or compacted in one portion of the mold box more than another, during the return movement of the charging device. As the shaft B continues to turn and the parts are brought into the position shown in Fig. 6, the pitman F is lifted 100 from contact with the roller F², and the slides I and lower die are permitted to move down sufficiently to form the necessary cavity in the mold box or casing to receive most of the charge of clay contained in the device 105 N. Such downward movement of the lower die is limited by a stationary but vertically adjustable stop S. In Fig. 7 the charging device is shown in position beneath the hopper G, the mold cavity containing the charge 110 of clay to be compressed and the pitman having begun its return movement toward the right, which movement acts to straighten the toggle L. The cam controlling the action of the bell crank M' is of such form 115 that during the movement of the shaft B effecting the adjustments represented in Figs. 5 to 7, no movement is imparted to the eccentric shaft K. The continued movement of the pitman toward the right from 120 the position shown in Fig. 7 acts to straighten the toggle and cause the upper die to enter the mold box or casing and lightly compress the charge of clay therein, the lower die being as previously stated 125 held from downward movement at this time by the stationary stop S coöoperating with its lower end.

As the shaft B rotates the pitman F carries the central pivotal connection of the 130

toggle L past the vertical line connecting the top and bottom toggle pivots, thus lifting the upper die slightly. During this movement the eccentric shaft K is rocked by the action of the bell crank M' shifting the arm M into the position shown in Fig. 8, thus shortening the distance between the upper end of the toggle L and the top of the mold box or casing, and lower die, the parts at this time being in the position shown in Fig. 8. The compression imparted to the clay by the straightening of the toggle just referred to is relatively light, being however, sufficient to remove the contained air therefrom and the slight upward movement of the upper die caused by the breaking of the toggle during the rightward movement of the pitman F from the position shown in Fig. 8 is sufficient to remove pressure from the clay and permit the air or "wind" therein entrapped to freely escape upwardly.

As the power shaft turns after breaking the toggle by rightward movement from the position shown in Fig. 8, it will be seen that after the pitman has reached the limit of such rightward movement and again moves toward the left, the toggle L will be again straightened to exert a second pressing action upon the clay within the mold box (the parts being then in the positions shown in Fig. 9) and owing to the adjustment of the eccentric shaft K above referred to this second compression will be materially heavier or more intense than the compression effected by the former or first straightening of the toggle. This final, heavier, compression completes the formation of the tiles and as the toggle is again broken by the continued leftward movement of the pitman, both of the dies are carried upward or into the positions shown in Fig. 4 with the completed tile in the path of the ejector connected to the charging device N.

To adapt the machine for making tile of different size and thickness the mold box or casing and the faces of the die may be provided with suitable liners or facing plates and also means are provided for positively varying the relation of or distance separating the dies. As shown, the stationary stop or abutment S of the lower die may be adjusted vertically by means of screws S' supported on the frame of the machine by hand wheels S²; and to permit of adjusting the upper die for different thicknesses of tile the eccentric shaft K is preferably mounted in an eccentric bushing T. This bushing is provided at its end with toothed segments T' with which mesh pinions T² on a shaft U. The bushing is surrounded by a sectional casing V formed as the top of the toggle L and with clamps the members of which are secured together by bolts V'. By loosening the bolts V' and manipulating the shaft U,

by means of a suitable wrench for example, the eccentric bushing T can be adjusted as required for determining the thickness of the tile and the parts secured in such adjusted position by again tightening the bolts V. Referring to Figs. 2 and 10 it will be seen that if the eccentric bushing T is rotated so that the section thereof of maximum thickness is above the shaft K, the toggle will be bodily adjusted vertically relative to the axis of said shaft and thereby the relation of the upper die to the lower die varied so that the machine will press a tile of different thickness from that which will be produced with the parts in relation shown in Fig. 10. The eccentric bushing T is made in two sections, each comprising a cylindrical member having at its outer end a toothed segment T'.

As indicated in Fig. 11, positive stops 85 may be provided for limiting downward movement of the upper die and in such event the lower die will be caused to move above the position which it would occupy during the first pressing operation, as previously 90 described, in order to effect such pressure. As the dies are separated at the completion of such first pressure, means are provided for limiting downward movement of the lower die, said means, as shown in Fig. 11, 95 comprising a longitudinally extensible latch R pivoted on a shaft R' mounted in bearings on the frame of the machine, and adapted to be moved to and from a position beneath a shoulder on the lower die. The shaft R' 100 is provided with an arm R² which is connected by a link R³ with one arm of a bell crank R⁴, the other arm of which has a roller extending into the path of a suitable cam R⁵ actuated by the main power shaft. 105 As the shaft rotates the cam R⁵ will actuate the bell crank R⁴ and rock shaft R' to move the latch R to and from position to limit downward movement of the lower die. While the dies are separated and the eccentric toggle 110 supporting shaft is being adjusted the tile will not be subjected to pressure from either of the dies and the air contained therein can therefore freely escape. The second or "re-press" movement first lowers the top die, as 115 far as permitted by the stops thereof, and then raises the lower die. At this time the cam F' contacting with the roller F² begins the ejecting movement of the lower die.

By the arrangement illustrated in Fig. 11, 120 it will be seen that the travel of the upper die will be stopped and the lower die raised to effect the first pressure and the lower die held within a fraction of an inch of the clay while the latter is relieved from the pressure of the upper die and the distance between the dies is varied for the second pressure. This results in the pressing of the tile near the top of the mold cavity and as the completed tile is required to travel a 125

shorter distance in being ejected from the mold than in the arrangement first described the corners of the tile are not so liable to be damaged as it is forced upward. This arrangement also provides for pressing the charge of clay first from the top, then from the bottom, then pressing both the top and bottom and finally applying pressure to the bottom as the tile is ejected.

10 It will be evident that the second "re-press" movement or compressing action might be obtained by means specifically different from those illustrated and described.

15 The press herein described is adapted for making various classes of architectural tile, such as wall, mantel or floor tile. This tile varies in size from 9 inches in length or width by $\frac{1}{4}$ inch to $\frac{5}{8}$ inch in thickness, to $\frac{3}{4}$ inch square by $\frac{1}{4}$ inch thick. Such tile are 20 made in many different conditions of clay varying from an ordinary native clay to fine English china clay in combination with flint and stone or other material necessary to produce a tile meeting the desired requirements. Such tile must, of course, be true 25 to size as determined, within small tolerances, and this necessitates that the press be of such character that the dies come together within a predetermined distance, regardless 30 of the varying quantity or temper of the clay and that the dies fit rather snugly within the mold case. The conditions, therefore, under which such presses must work and the material to be acted upon differ greatly from 35 those which are present in the manufacture of brick and for these reasons presses having many parts generally similar to those hereinbefore described, although adapted to manufacturing bricks, are not capable of 40 satisfactory use in pressing tile.

Having described my invention what I claim and desire to secure by Letters-Patent is,

1. In a tile press, the combination of upper and lower dies, an eccentric shaft, a single toggle having its members respectively connected to one of the dies and to said shaft, means for extending and breaking the toggle to operate the dies twice during 45 each cycle of operation, and means for automatically turning the eccentric shaft to vary the relation between the toggle actuated die and the other die between the successive pressing movements of the dies occurring 50 during each cycle of operation, for the purpose described.

2. In a tile press, the combination of upper and lower dies, a single toggle having its lower end connected with the upper die, 60 means for extending and breaking the toggle to shift the upper die to and from operative relation to the lower die twice during each cycle of operation, and means for automatically varying the distance between the upper die and the upper axis of the toggle 65

between the successive pressing actions occurring during each cycle of operation independent of that due to movement of the toggle, for the purpose described.

3. In a tile press, the combination of a lower die, an upper die, a toggle having one member connected to the upper die and its other member connected to bars or rods attached to and extending upward from the support for the lower die, a power shaft, 70 means connecting the shaft and toggle and adapted to extend and break the toggle twice during each rotation of the shaft, means for effecting simultaneous vertical movement of the two dies, and means for varying the relation of the toggle to the bars or rods connecting it with the lower die between the successive pressing operations imparted to the toggle during each rotation of the shaft, whereby the second of said pressing operations will be stronger than the first.

4. In a tile press, the combination of an upper die, a lower die, bars or rods attached to opposite sides of and extending upward from the support for said die, an eccentric 90 shaft journaled in bearings in said bars, a toggle having one member connected with the upper die and its other member engaging said eccentric shaft, a power shaft, means connecting the power shaft and toggle and 95 adapted to extend and break the toggle twice during each rotation of the shaft, means for effecting simultaneous vertical movement of the two dies, and means actuated by the power shaft for imparting rotary 100 movement to said eccentric shaft between the successive pressing operations imparted to the toggle during each rotation of the power shaft, for the purpose described.

5. In a tile press, the combination of an upper die, a lower die, bars or rods attached to opposite sides of and extending upward from the support for the lower die, a toggle having one member connected to said bars and its other member connected to the upper 110 die, a power shaft, a pitman connecting the toggle with means on the power shaft adapted to reciprocate the pitman to extend and break the toggle twice during each rotation of the shaft, means coöperating with the pitman for effecting simultaneous vertical movement of both dies, and means for varying the relation of the toggle to the bars connecting it with the lower die between the two 115 pressing operations imparted to the toggle 120 during each rotation of the shaft, whereby the second of said pressing operations will be more powerful than the first.

6. In a tile press, the combination with upper and lower dies, of bars or rods connected with one die and extending past the other die, a toggle having one member connected with the last said die and its other member connected with said bars, a power shaft, means connecting the power shaft and 125 130

- toggle and adapted to extend and break the toggle twice during each rotation of the shaft, means for effecting simultaneous vertical movement of both dies, and means for varying the positions of the toggle and die connected therewith relative to the other die between the two pressing operations imparted to the toggle during each rotation of the shaft, for the purpose described.
- 10 7. In a tile press, the combination of upper and lower dies, a single toggle for actuating one of said dies, means for extending and breaking the toggle to move the die connected therewith to and from pressing relation to the other die twice during each cycle of operation, and means for automatically effecting bodily longitudinal movement of the toggle between the successive pressing actions occurring during each cycle of operation, for the purpose described.
- 15 8. In a tile press, the combination of a lower die, an upper die, a toggle having one member connected to the upper die and its other member supported by an eccentric shaft, a power shaft, means connecting the power shaft and toggle and adapted to extend and break the latter twice during each rotation of the shaft, an arm attached to said eccentric shaft, and means connecting said arm and the power shaft, whereby the eccentric shaft will be adjusted to vary the position of the toggle and upper die relative to the lower die between the successive pressing operations imparted to the toggle during each rotation of the power shaft.
- 20 9. In a tile press, the combination of a lower die, an upper die, a toggle having one member connected to the upper die and its other member supported by an eccentric shaft, a power shaft, means connecting the power shaft and toggle and adapted to extend and break the latter twice during each rotation of the shaft, a bell crank having one arm connected to the eccentric shaft, and a cam rotated by the power shaft and engaging the other arm of the bell crank, whereby the eccentric shaft will be adjusted to vary the position of the toggle and upper die relative to the lower die between the successive pressing operations imparted to the toggle during each rotation of the power shaft.
- 25 10. In a tile press, the combination of a lower die, an upper die, a toggle lever having one member connected to the upper die and its other member supported by an eccentric shaft, a power shaft, a pitman connected with the toggle, means rotated by the power shaft and engaging the pitman to reciprocate the latter and extend and break the toggle twice during each rotation of the power shaft, means for simultaneously moving both dies vertically, and connections between the power shaft and the eccentric toggle supporting shaft whereby the eccentric shaft will be adjusted to vary the position of the toggle and upper die relative to the lower die between the successive pressing operations imparted to the toggle during each rotation of the power shaft.
- 30 11. In a tile press, the combination of a lower die, an upper die, a toggle lever having one member connected to the upper die and its other member supported by an eccentric shaft, a power shaft, a pitman connected with the toggle, a crank rotated by the power shaft and engaging the pitman to reciprocate the latter and extend and break the toggle twice during each rotation of the power shaft, means for simultaneously moving both dies vertically, a bell crank having one arm connected to said eccentric shaft, and a cam rotated by the power shaft and engaging the bell crank, whereby the eccentric shaft will be adjusted to vary the position of the toggle and upper die relative to the lower die between the successive pressing operations imparted to the toggle during each rotation of the power shaft.
- 35 12. In a tile press, the combination of a lower die, an upper die, a toggle having one member connected to the upper die and its other member supported by an eccentric shaft, a power shaft, means connecting the power shaft and toggle and adapted to extend and break the latter twice during each rotation of the shaft, means connecting the eccentric shaft and power shaft and adapted to rock the eccentric shaft between the successive pressing operations imparted to the toggle during each rotation of the power shaft, and an adjustable eccentric bearing for the eccentric shaft, for the purpose described.
- 40 13. In a tile press, the combination of an upper die, a lower die, bars or rods attached to opposite sides of the support for the lower die and extending upward above the upper die, an eccentric shaft mounted in bearings in said bars, an eccentric bushing on said shaft, a toggle having one member embracing said shaft and bushing and its other member connected to the upper die, a power shaft, connections between the power shaft and toggle adapted to extend and break the toggle twice during each rotation of the shaft, means connecting the power shaft and said eccentric shaft and adapted to adjust the latter to vary the position of the toggle and upper die relative to the lower die between the successive pressing operations imparted to the toggle during each rotation of the power shaft, and means for adjusting the eccentric bushing, for the purpose described.
- 45 14. In a tile press, the combination of a lower die, an upper die, a toggle having one member connected to the upper die and its other member connected to bars or rods attached to and extending upward from the

- support for the lower die, a power shaft, means connecting the shaft and toggle and adapted to extend and break the toggle twice during each rotation of the shaft, 5 means for effecting simultaneous vertical movement of the two dies, a stop limiting downward movement of the upper die, a stop for limiting downward movement of the lower die when the dies are separated 10 between the two pressing operations obtained during each rotation of the power shaft, and means for moving said stop to inoperative position at the completion of the second of said pressing operations.
- 15 15. In a tile press, the combination of a lower die, an upper die, a toggle having one member connected to the upper die and its other member connected to bars or rods attached to and extending upward from the 20 support for the lower die, a power shaft, means connecting the shaft and toggle and adapted to extend and break the toggle twice during each rotation of the shaft, means for effecting simultaneous vertical movement of the two dies, a stop limiting downward movement of the upper die, a pivotally mounted stop adapted to be adjusted into position to limit downward movement of the lower die when the dies are separated 25 between the two pressing operations obtained during each rotation of the power shaft, and a cam rotated by the power shaft for moving said stop into operative position as described and returning it to inoperative position at the completion of the second of said pressing operations.
- 30 16. In a tile press, the combination of a lower die, an upper die, a toggle having one member connected to the upper die and its other member connected to bars or rods attached to and extending upward from the support for the lower die, a power shaft, means connecting the shaft and toggle and adapted to extend and break the toggle twice 35 during each rotation of the shaft, means for effecting simultaneous vertical movement of the two dies, a stop limiting downward movement of the upper die, a pivotally mounted, longitudinally extensible, stop 40 adapted to be adjusted into position to limit downward movement of the lower die when the dies are separated between the two pressing operations obtained during each rotation of the power shaft, and a cam rotated by the 45 power shaft for moving said stop into operative position as described and returning it to inoperative position at the completion of the second of said pressing operations.
- 50 17. In a tile press, the combination of upper and lower dies, a toggle connected with one of the dies, means for extending and breaking the toggle to move the die connected therewith to and from pressing 55 relation to the other die twice during each

cycle of operation, means for automatically 65 effecting adjustment of the toggle between the successive pressing actions occurring during each cycle of operation to cause the dies to impart a relatively light compression to the material between them, relieve such material from pressure and thereafter impart a 70 second and materially heavier compression to such material, and means adapted to vary the relation of the toggle and connected die to the other die in accordance with variations in the thickness of the charge of material to be pressed.

18. In a tile press, the combination of upper and lower dies, a toggle connected with one of the dies, means for extending 80 and breaking the toggle to move the die connected therewith to and from pressing relation to the other die twice during each cycle of operation, means for automatically effecting adjustment of the toggle between the 85 successive pressing actions occurring during each cycle of operation to cause the dies to impart a relatively light compression to the material between them, relieve such material from pressure and thereafter impart a 90 second and materially heavier compression to such material, and means eccentrically adjustable about the stationary axis of the toggle for varying the relation of the toggle and connected die to the other die to 95 adapt the press to operate on charges of different thickness.

19. In a tile press, the combination of upper and lower dies, an eccentric shaft, a toggle having one member fulcrumed about 100 the eccentric portion of said shaft and its other member connected with one of the dies, means for extending and breaking the toggle to compress a charge of material between the dies twice during each cycle of operation, means for automatically rocking the eccentric shaft between the successive pressing actions occurring during each cycle of operation, and independently adjustable means between said shaft and toggle for 105 varying the relation of the toggle and the connected die to the other die in accordance with the thickness of the tile to be produced.

20. In a tile press, the combination of upper and lower dies, an eccentric shaft, a toggle having one member fulcrumed about the eccentric portion of said shaft and its other member connected with one of the dies, means for extending and breaking 115 the toggle to compress a charge of material between the dies twice during each cycle of operation, means for automatically rocking the eccentric shaft between the successive pressing actions occurring twice 120 during each cycle of operation, and an eccentric bushing arranged between said shaft and the surrounding portions of the toggle 125

and adjustable relative to the shaft and toggle to adapt the press to produce tile of different thickness.

21. In a tile press, the combination of upper and lower dies, an eccentric shaft, a toggle having one member fulcrumed about the eccentric portion of said shaft and its other member connected with one of the dies, means for extending and breaking the toggle to compress a charge of material between the dies, means for automatically rocking the eccentric shaft between successive pressing operations, and adjustable means for varying the intensity of the pressures exerted by the two successive pressing operations.
22. In a tile press, the combination of upper and lower dies, an eccentric shaft, a toggle having one member fulcrumed about the eccentric portion of said shaft and its other member connected with one of the dies, means for extending and breaking the toggle to compress a charge of material between the dies twice during each cycle of operation, and means for automatically rocking the eccentric shaft between the successive pressing actions occurring during each cycle of operation, including an adjustable member adapted to alter the relation between the eccentric shaft and toggle when the parts are at rest whereby the intensity of the pressures obtained by the successive pressing operations will be varied.
23. In a tile press, the combination of upper and lower dies, an eccentric shaft, a toggle having one member fulcrumed about the eccentric portion of said shaft and its other member connected with one of the dies, a power shaft, means connecting the power shaft and toggle and adapted to extend and break the latter twice in each rotation of the shaft, an arm attached to the eccentric shaft, and means connecting said arm and the power shaft, whereby the eccentric shaft will be adjusted to vary the position of the toggle and connected die relative to the other die between the successive pressing operations occurring during each revolution of the power shaft, said means including an adjustable member whereby the intensity of the pressures exerted by said pressing operations may be varied.
24. In a tile press, the combination of a lower die, an upper die, a toggle for moving one of said dies toward and from the other, a power shaft, means connecting the shaft and toggle and adapted to extend and break the toggle twice during each rotation of the shaft, means for varying the relation of the toggle and die connected therewith to the other die in accordance with the thickness of the tile to be produced, and means for varying the relative intensity of the pressing actions.
25. In a tile press, the combination of upper and lower dies, an eccentric shaft, a toggle having one member fulcrumed about the eccentric portion of said shaft and its other member connected with one of the dies, means for extending and breaking the toggle to compress a charge of material between the dies twice during each cycle of operation, means for automatically rocking the eccentric shaft between the successive pressing operations occurring during each cycle of operation, adjustable means for varying the relative intensity of the pressures exerted by such successive operations, and an eccentric bushing arranged between the eccentric shaft and toggle and adjustable relative thereto to adapt the press to produce tile of different thickness.
- In testimony whereof I affix my signature in presence of two witnesses.

FRANK B. YINGLING.
